[57] CLAIM

The ornamental design for liquor treating apparatus, as shown and described.

DESCRIPTION

FIG. 1 is an isometric view showing the ornamental design for a liquor treating apparatus according to the present invention.

FIG. 2 is top plan view of the liquor treating apparatus of FIG. 1.

FIG. 3 is a front elevation view of the liquor treating apparatus of FIG. 1.

FIG. 4 is a right side elevation view of the liquor treating apparatus of FIG. 1.

FIG. 5 is a left side elevation view of the liquor treating apparatus of FIG. 1, and;

FIG. 6 is a rear elevation view of the liquor treating apparatus of FIG. 1.

The bottom view of the liquor treating apparatus of FIG. 1 is plain and unornamental.
